CRUSH DRESSING MECHANISM

Ernest V. Flanders and Carroll H. Drury, Springfield, Vt., assignors to Jones & Lamson Machine Company, Springfield, Vt., a corporation of Vermont

Continuation of application Serial No. 686,470, July 26, 1946. This application January 22, 1953, Serial No. 332,706

11 Claims. (Cl. 51—5)

1

This invention relates to mechanism for crush dressing grinding wheels.

One object of the invention is to provide mechanism interchangeable with diamond dressing mechanism in a grinding machine.

A further object is to provide hydraulic pressure means for forcing the crushing roll against the grinding wheel, together with means for advancing the crushing roll independently of the fluid pressure means to compensate for wheel wear and crushing.

Still another object is to provide for stopping the rotation of the wheel for the presentation thereto of the crushing roll, after which the wheel is rotated in either direction desired at a relatively slow crushing speed.

A further object is to provide for automatic resumption of full speed grinding wheel rotation in grinding direction after crushing has proceeded to the desired extent.

Still another object is to provide means whereby the crushing pressure may be adjusted to suit the width and profile of the grinding wheel and other conditions.

Still another object is to provide an improved cycle of control of the crushing roll and grinding wheel.

For a complete understanding of this invention, reference may be had to the accompanying drawings in which:

Figure 1 is a longitudinal vertical sectional view through the crushing mechanism and related parts, a portion of the grinding wheel being shown.

Figure 2 is a rear end elevation of the same.

Figure 3 is a detail sectional view on line 3—3 of Figure 1.

Figure 4 is a detail sectional view to a larger scale on line 4—4 of Figure 2.

Figure 5 is a detail sectional view to a larger scale on line 5—5 of Figure 6.

Figure 6 is a detail sectional view on line 6—6 of Figure 1.

Figure 7 is a view similar to a portion of Figure 6 but showing a modified construction.

Figure 8 is a fragmentary end elevation of the crusher roll mounting of Figure 7.

Figure 9 is a fragmentary sectional view illustrating corresponding faces of the grinding wheel and the crushing roll.

Figure 10 is a wiring diagram of the grinding wheel drive and crushing mechanism, illustrating the cycle of operations.

This invention is shown as applied to a thread grinding machine of the type shown in Flanders

2

Patent No. 2,184,011, granted December 19, 1939, and the crush truing mechanism of this invention is arranged to be interchangeable with the diamond truing mechanism shown in that Flanders patent.

At 1 is shown the cradle having a forward portion which partially surrounds the grinding wheel 2 rearwardly from the work. This cradle has a tubular extension 3 within which the truing mechanism is placed. In accordance with this invention this truing mechanism comprises a cylindrical casing 4 arranged to be inserted within the tubular extension 3 as far as permitted by the engagement of a circular flange 5 on the casing 4 against the rear end of the extension 3. These parts may be secured together with capacity for limited angular adjustment by screw and slot connections 5a. This casing 4 contains or supports the wheel crushing mechanism. This 10 casing is provided with a pair of transverse partitions 6 and 7 provided with bushings 8 for slidably mounting a ram 9. The forward end of this ram is provided with a head 10 within which is journaled the crushing roll 11, and when this 15 crushing roll is intended to crush the grinding wheel 2 to multiple rib form, as for thread grinding, it will be provided with complementary ribs. The partition 6, except for the opening where the bushing 8 is positioned, is solid and the rear 20 end portion of the head is connected to the forward end of the bushing as by a flexible diaphragm 12, thereby to prevent detritus from the wheel from entering back of the partition 6.

The rear end of the ram 9 is hollow and has 25 fixed thereto a nut 14 threaded for the reception of the forward end of a threaded rod 15. This rod 15 is the piston rod of a piston 16 which is slidably within a hydraulic cylinder 17. The piston rod 15 extends through the head 10 of this cylinder through a packing gland 18, and has a splined portion on which is mounted a correspondingly splined gear 20. This gear is 30 coupled through an idler 21, journaled on a stub shaft 22, to a gear 23 carried by a shaft 24 coupled as through the coupling elements 25 and 26 with a shaft 27. This shaft 27 forms a portion of the wheel feed mechanism and corresponds to the shaft 51 of the Flanders Patent No. 2,184,011. This shaft has a threaded portion 28 35 threaded through a lug 29 upstanding from a portion 30 of the grinding machine frame and it also has fixed thereto a gear 31 meshing with a long gear 32 carried by shaft 33, which, in turn, has meshing therewith a gear 34 carried by a shaft 35. This corresponds to the shaft 45 of

the Flanders Patent No. 2,184,011, and this is turned in time with the traverse of the work for a predetermined angular distance which allows the entire truing mechanism to be advanced toward the grinding wheel by the amount of axial motion of the shaft 21. This provides for feed of the truing mechanism to provide for wheel wear and truing in the well known manner. It will be noted that when this shaft 35 is turned, the shaft 15 is also turned, the turning of this shaft 15 advancing the ram 9 with relation to the piston 16 by the amount of advance of the truing mechanism, and this is entirely independent of the axial position of the piston 16 within the hydraulic cylinder 17.

The hydraulic cylinder 17 with its piston 16 provides for applying crushing pressure of the dressing roll 11 against the grinding wheel, this pressure being exerted first while the grinding wheel is stationary and then during a relatively slow rotation of the grinding wheel by means which will later appear, until the crushing has been effected to the desired extent.

The hydraulic pressure is derived from a pump 40 (see Figure 3) which takes oil from the interior of the casing 4 through an inlet port 41 and discharges through a pipe 42 into a valve chamber 43 (see Figure 1). This pump 40 is operated by a drive shaft 44 provided at its upper end with a worm wheel 45. With this worm wheel meshes a worm 46 on a horizontal shaft 47 journaled laterally in the upper portion of the casing 4 and extending outwardly therefrom at one end, as shown in Figure 3, where it is provided with a belt pulley 48 keyed thereto. This pulley 48 is connected by a drive belt 49 with a motor 50 carried by the casing 4 back of the flange 5. Whenever this motor 50 is driven, fluid under pressure is delivered from the pump 40 through the pipe 42 to the valve chamber 43 against the forward end of a valve 52 (see Figure 1) which is normally spring pressed forwardly as by a spring 53 reacting between its rear end and the rear wall of the casing 43. When this valve 52 is pressed rearwardly sufficiently, hydraulic pressure is delivered from forwardly of its forward face through the passage 55 past a ball check valve 56 and through passages 57 and 58 to the interior of the cylinder 17 rearwardly of the piston 16, thus to drive the piston 16 forwardly and press the crushing roll 11 against the grinding wheel.

The amount of pressure exerted against the piston 16 may be adjusted in accordance with the length and contour of the crushing surfaces, or for other reasons, and for this purpose there is shown in Figure 3 the rear end of the cylinder 17 which communicates through a passage 60 with a ball valve 61. This valve is pressed toward seating position by a slide 62 within a casing 63 and the slide is adjustably loaded by a spring 64, the outer end of which engages a head of an abutment member 65. The outer end of this member 65, is, in turn, engaged by a screw 66 threaded through a closure plug 67 for the casing 63. This valve 61 controls a discharge passage 68 leading back into the interior of the casing 4. By loading this valve 61 to the desired extent, the maximum hydraulic pressure back of the piston 16 may be regulated as desired.

The rear end of the cylinder 17 is also provided with a small continuously open bleeder port 69 (Figure 1) leading out to the interior of the casing 4, so that whenever the pump 40

stops operating, the fluid pressure leaks off from back of the piston 16 and permits the ram and the crush dressing tool to be retracted from the grinding wheel. This retraction is accomplished by springs 70 (Figure 6) secured at their rear ends to pins 71 in the rear wall 72 of the casing 4, and extended through perforations 73 through the partition 7 and having their forward ends engaged in the heads of pins 74 secured in a clamp collar 75 surrounding and clamped to the ram 9 as by the clamping bolt 76. The collar 75, as shown, is provided with a notch 78 which takes over a guide pin 79 projecting rearwardly from the partition 6, thus preventing undesired turning of the ram 9 which would bring the ridges of the crushing roll 11 out of proper alignment with the ridges of the grinding wheel 2. This clamping of the ring 75, however, permits such angular adjustment of the ram 9 as may be necessary.

The rear end of the casing 4 is closed off by a cap 80 which is secured to the rear end of the casing 4, as by the long screws 81 which pass through arcuate slots 82 in the cap 80 and are threaded into the casing 4. This permits limited angular adjustment of the casing 4 with reference to the cap 80, the angular position of which is determined by sliding engagement with the guide bar 83 of the grinding machine. This cap carries the journal 22 for the idler gear 21 and also the bearing for the shaft 24. It also carries certain of the control mechanism as will later appear.

Angular adjustment of the casing 4 with respect to the extension 3 and the cap 80 to line up the crushing roll ridges with the grooves of the grinding wheel as when the wheel is inclined to the helix angle of the work, may be produced, when the screw connections of 5a and 82 are loosened, by turning a shaft 85 journaled in the cap 80 (see Figure 4) and provided with a squared rear end 86 for engagement with a wrench, this shaft 85 having keyed to its inner end a pinion 87 meshing with an arcuate rack bar 88 secured to the casing 4 as by means of one or more screws 89. Mating scales 91 and 92 on the cradle and flange 5, respectively, show the extent of such adjustment.

The control mechanism hereinbefore mentioned carried by the cap 80 comprises a pair of limit switches 15LS and 16LS between which is rockable an actuating arm 100 fixed to a rock shaft 101. This rock shaft 101 also has depending therefrom a dog 102 which extends down forwardly of a conical abutment 105 adjustable axially on the rear portion of the splined piston rod 15. This abutment 105 has engaged against its outer face a large diameter nut 106 threaded on a reduced diameter portion 107 of the rod 15. A set screw 108 passing radially through the nut 106 may be employed to lock the nut in adjusted position on the rod. This abutment 105 is so positioned as to impinge upon the dog 102 when the crushing roll ram approaches its desired limit of crushing position, thereby rocking the dog 102 and consequently the shaft 101 and the arm 100 inwardly, allowing the switch 16LS to open and thereafter closing the switch 15LS, while on the reverse direction of motion of the rod 15 as the ram retracts, the switch 15LS is allowed to open, after which the switch 16LS is closed. The periphery of the nut 106 may be graduated to cooperate with an index mark on the abutment 105 to indicate the position of adjustment axially of the rod 15 of the abutment

105. It will be noted that no matter what the angular position of the rod 15 may be, this rod being turned by angular increments with the feed of the wheel toward the work as previously mentioned, the abutment is effective to operate the dog 102 in one direction. A spring 110 engaging a post 111 carried by the upper end of the arm 100 and a fixed post 112, acts to swing the lower end of the arm 100 and the dog 102 backwardly as far as permitted by a stop 114 carried by the upper end of the arm 100 which impinges against the outer face of the cap member 80.

Figure 7 illustrates a modified mechanism for determining the angular adjustment of the ram 9. It comprises a ring member 120 adapted to be clamped about the ram 9 and provided with an index at 121 which cooperates with a datum line 122 on an extension 123 of the clamp 75 to which the retracting springs 70 are attached. On loosening the clamp 75, the angular position of the ram, and consequently of the crushing roll, may be adjusted. This avoids the rack and gear adjustment of Figures 2 and 4, but it is not so accessible. This figure and Figure 8, also, show a mounting for the crusher roll which is adjustable axially of the roll so as to make it possible to directly align the complementary faces of the crusher roll and grinding wheel. As shown therein the crusher roll 11a is carried by a rotary spindle 130 mounted for rotation in a bearing member 131 carried by a slide 132. This slide is provided with a dovetail portion 133 which slides in a correspondingly shaped way 134 on a bracket 135 fixed to the ram 7 and transverse to the axis of this ram so that the slide 132 may be adjusted laterally of the ram axis. Such adjustment may be produced by turning an adjusting screw 136 journaled in an end wall 137 of the bracket 135 and threaded into the slide 132. This arrangement permits the roll to be adjusted axially so as to bring its peripheral ridges 140 directly opposite to the valleys 141 of the grinding wheel as shown best in Figure 9.

The various mechanisms of the crush dressing structure hereinbefore described are caused to operate in a semi-automatic cycle of operations, and the switches 15LS and 16LS form portions of the control of this driving mechanism. The power for the cycle is derived from either of two sources, one comprising two lines of a three-phase alternating power system, these two lines being indicated at 200 and 201 of Figure 10. The normally open switch 15LS is directly across these lines and is in circuit with a coil 206 of a timing switch 190. Also across the lines 200 and 201 is a rectifier at 191, the direct current terminals of which furnish the power source for a slow rotation of the grinding wheel during truing. The power for normal wheel drive for grinding is taken from the direct current lines 203 and 204.

Sequence of operation for crush dressing

The wiring diagram of Figure 10 shows the parts with the wheel motor 150 running at grinding speed, deriving energy from the direct current lines 203 and 204. The conditions are as follows: the circuit is closed from the D. C. line 203 through lead 205, coil of relay 31CR, lead 206 through closed wheel stop switch 207, leads 208 and 209 through closed switch arm 210 of the relay 31CR, leads 211 and 212 to the D. C. line 204. This same closed switch 210 connects from the line 203 through leads 205, coil 213

of the coolant motor switch 21M, lead 214, closed switch arm 210, leads 211 and 212 to the D. C. line 204. Closing of the switch 21M causes the coolant motor 215 (which supplies coolant to the wheel and work in the well known manner) to be energized from the D. C. line 203, lead 205, coolant motor 215, closed switch 21M, leads 216 and 217 to the D. C. line 204. Coils of relays 31M1 and 31M2 are closed, the circuit being from the D. C. line 203 through lead 205, coil of the relay 31M1 and coil of the relay 31M2 in parallel with each other, lead 220, closed switch 221 of the relay 32M1, lead 222, closed switch 223 of the relay 33CR, lead 224, closed switch 225 of the relay 31CR, leads 226, 211 and 212 to D. C. line 204. Energization of the coils of 31M1 and 31M2 closes a circuit from the D. C. line through the wheel motor 150 armature and series field as follows: from line 203, lead 205 to lead 227, closed switch 228 of the relay 31M2, lead 229, resistance control 31FA, lead 230, closed switch 231 of relay 31A, lead 232, armature 233 of the wheel motor 150, lead 234, closed switch 235 of the relay 32M1, lead 236, series field 237, leads 238 and 239, closed switch 240 of the relay 31M1, leads 241 and 217 to the D. C. line 204.

Energization of the coil of the relay 31FA energizes the shunt field of the wheel motor 150 from the D. C. line 203, lead 245, switch 246 of the relay 31FA, lead 247, shunt field 248 and lead 249 and 217 to the line 204.

The dressing cycle

When crush dressing is desired, the grinding wheel is first stopped by pressing the stop button 207. This interrupts current through the coil of the relay 31CR which opens the switch 210 which supplies current to the coolant motor control coil 213. This allows the switch 21M to open which permits the coolant motor 215 to coast to stop.

Deenergization of the coil of the relay 31CR also interrupts current through the coils of the relays 31M1 and 31M2 at the switch 225.

Deenergization of the coils of relays 31M1 and 31M2 interrupts current flow through the motor armature 233. The shunt field 248 remains energized. The coil of the relay 31M1 being deenergized, the switch 255 closes, which makes a closed path including the wheel motor armature 233 and the braking resistor 3R3 as follows: closed switch 255, lead 256, resistance 316 of 31RC, lead 257, resistor 3R3, lead 258, motor armature 233, lead 234, closed switch 235 of the relay 32M1, lead 236, series field 237; leads 238 and 239, back to the closed switch 255. The wheel motor 150 thus stops by dynamic braking.

Switch 2LS is closed when the truing feed mechanism is to be operated. Closing of this switch 2LS closes a circuit through the coils of the relays 2CR and 32CR as follows: from direct current line 203 to leads 265 and 266, coil of the relay 32CR, lead 267, switch 268 of the relay 16CR, lead 269, closed switch 270 of the relay 16CR, leads 271 and 272, closed switch 2LS, leads 273 and 212 back to the D. C. line 204, this being the circuit for the relay coil 32CR. For the relay coil 2CR the circuit is from the line 203, leads 265, 266 and 274, coil of the relay 2CR, leads 275, 276 and 267, closed switch 269 of the relay 5CR, lead 269, closed switch 270 of the relay 16CR, leads 271 and 272, closed switch 2LS, leads 273 and 212 to the D. C. line 204.

Energization of the coil of the relay 2CR starts the truing device pump motor 50 which

feeds the crushing roll against the grinding wheel by closing of the switch 279 from D. C. line 203, lead 276, coil of relay 41M, lead 277, switch 279, leads 286 and 314 back to D. C. line 204. Energization of the coil of relay 41M closes the switch 280 which starts the truing device motor from D. C. line 203, the motor 50, switch 280, lead 278 to D. C. line 204. The relays 2CR and 32CR are maintained energized by a holding circuit through the switch arm 285 of the relay 2CR as follows: from the D. C. line 203, leads 265 and 266, coil of the relay 32CR, lead 267, closed switch 268 of the relay 5CR, lead 269, closed switch 270 of the relay 16CR, lead 271, switch 285 of the relay 2CR, leads 286 and 212 to the D. C. line 204. This by-passes the switch 2LS which can now open without opening this circuit.

Energization of the coil of the relay 32CR energizes the relays 32M1 and 32M2 as follows: from D. C. line 203 to lead 205, coil of the relay 32M1 and 32M2 in parallel, leads 290, 291, closed switch 292 of the relay 31RC, lead 293, closed switch 294 of the relay 31M2, lead 295, closed switch 296 of the relay 32CR, leads 297 and 224, closed switch 225 of the relay 31CR, leads 226, 211 and 212 to the D. C. line 204. Energization of the relays 32M1 and 32M2 closes the switch arms 300 and 301 which permits closing of the circuit to the wheel motor armature 233 from the D. C. rectifier lines 302 and 303 upon closing of the wheel start switch 318 as will later appear.

Energization of the coil of the relay 32CR closes a switch 280 which closes a circuit from the D. C. line 203 through lead 265, coil of the relay 33CR, lead 281, closed switch 280 of the relay 32CR, leads 282 and 212 to the line 204. This energizes the coil of the relay 33CR, and this, in turn, opens a switch arm 223 of this relay which breaks the circuit through the coils of relays 31M1 and 31M2 which acts to disconnect the wheel motor 150 from the D. C. lines 203 and 204.

Closing of the relay 32CR energizes the shunt coil 310 of the relay 31RC from the D. C. line 203, lead 265, coil 310 of the relay 31RC, lead 311, switch 312 of the relay 32CR and leads 313, 314 and 312 to the D. C. line 204. This closes the switch 292 unless this is prevented by braking current flow through the series coil 316 of the relay 31RC. The rectifier is thus guarded against pumping back through the braking current of the wheel motor should the motor not be stopped. As soon as the switch 292 closes, the apparatus is conditioned for starting the grinding wheel rotation for crushing, which is started by pressing the wheel start button. The crushing roll is now pressing against the stationary grinding wheel.

The wheel start button 318 is now closed by the operator, which energizes the coil of the relay 31CR from the D. C. line 203 through lead 205, coil of the relay 31CR, lead 206, closed switch 207, lead 208, wheel start button 318 and leads 319 and 212 to the D. C. line 204. The relay 31CR is maintained closed through a holding circuit including the switch 210, the circuit being from the D. C. line 203 through lead 205, coil of the relay 31CR, lead 206, closed stop switch 207, leads 208 and 209, switch 210 of the relay 31CR, leads 211 and 212 to the D. C. line 204.

Energization of the relay 31CR energizes the coil of the relay 21M which starts the coolant motor as previously described.

Energization of the relay 31CR also energizes the coils 32M1 and 32M2 through the relays 32CR, 31M2 and 31RC which connects the wheel

motor to the rectifier leads 302 and 303 as follows: from rectifier lead 302 through switch arm 300 of the relay 32M1, lead 325, variable resistor 326, leads 327 and 328, wheel motor armature 233, lead 258, lead 329, switch 301 of the relay 32M2 to the rectifying lead 303.

Energization of the relay 32M1 opens the switch arm 325 which opens the circuit through the series field, leaving the shunt field energized. The wheel motor now drives the wheel at slow crushing speed and in a direction determined by the connection of the rectifier leads 302 and 303 to the rectifier. Reversing these leads, reverses the direction of crushing rotation of the grinding wheel. By driving the wheel during crushing in the reverse direction to grinding so that the contact between wheel and roll is moving downwardly, no lifting effect on these parts is produced so that no hold down devices are necessary and clearing of the wheel from crushed particles is facilitated.

It will be noted that the wheel driving motor 150 is cut off from both D. C. lines 203 and 204 by opening switches 223 of the relay 31M2 and 240 of the relay 31M1. This is a safety feature which guards against D. C. line voltage stresses in the rectifier.

The constant hydraulic pressure derived from the pump 40 driven by the pump motor 50 is now applied to the crusher roll while the grinding wheel rotates at low speed and in the desired direction, and this continues crushing the grinding wheel to shape until the limit switch 16LS is opened by the hydraulic feed mechanism as the wheel approaches size. Opening of this switch 16LS would deenergize the coil of the relay 33CR, the circuit being from the D. C. line 203 through lead 265, coil of the relay 33CR, lead 335, switch 336 of the relay 33CR, lead 337, switch 16LS, and leads 338 and 212 to the D. C. line 204, except that the coil of the relay 32CR is now energized.

As the wheel reaches size, however, the micro switch 15LS is engaged and closed by the feed mechanism which starts the timing device T, and during the time interval before the timing switch T closes, the entire wheel is crushed smoothly to size.

At the end of the set time, closing of the time switch T energizes the coil of the relay 16CR as follows: From the D. C. line 203, through lead 265, coil of the relay 16CR, lead 340, switch 341 of the timer T, leads 342 and 217 to the D. C. line 204. Energizing of the coil of the relay 16CR opens the switch 270 of the relay 16CR which breaks the circuit to the coil of the relays 2CR and 32CR.

Deenergization of the coil of the relay 2CR deenergizes the coil of relay 41M, allowing the switch 280 to open and stop the truing device pump motor 50. The hydraulic pressure in the cylinder 17 now bleeds off, and the springs 70 retract the crushing roll from the wheel.

Deenergization of the coil of the relay 32CR now that switch 16LS is also open, deenergizes the coils of the relays 33CR, 32M1 and 32M2 which disconnect the wheel motor 150 from the rectifier.

The relay 32M1 being now deenergized, the braking resistors 3R2 and 3R3 are connected in series to the motor armature to stop the wheel motor 150 by dynamic braking.

The withdrawal of the crushing roll allows the switch 15LS to open and thereafter causes the switch 16LS to be engaged and closed.

This deenergizes the coil of the relay 33CR which closes the switch 223 of this relay, again energizing the coils of the relays 31M1 and 31M2 which connect the grinding wheel motor 150 across the D. C. lines 203 and 204 as first described, so that the wheel motor resumes grinding speed in grinding direction.

From the foregoing description of certain embodiments of this invention it should be evident to those skilled in the art that various further changes and modifications might be made without departing from the spirit or scope of this invention.

We claim:

1. In combination with the rotary grinding wheel of a grinding machine, a wheel truing mechanism comprising a crushing roll, means supporting said roll on said machine for rotation about an axis substantially parallel to that of said wheel and for motion toward and from said wheel, a fluid pressure motor connected to said roll for moving said roll against said wheel and there holding it under pressure from said fluid, said motor having a continuously open bleeder port for the escape of fluid under pressure therefrom, means biasing said roll to a position retracted from said wheel, a source of fluid, a fluid conductor circuit between said source and motor, a pump in said conductor circuit for pumping fluid from said source to said motor, and means connected thereto for controlling the operation of said pump.

2. In combination with a rotary grinding wheel of a grinding machine, a wheel truing mechanism comprising a crushing roll, means supporting said roll on said machine for rotation about an axis substantially parallel to that of said wheel and for motion toward and from said wheel, a fluid pressure motor connected to said roll for moving said roll against said wheel and there holding it under pressure from said fluid, said motor having a continuously open bleeder port for the escape of fluid under pressure therefrom, means connected thereto biasing said roll to a position retracted from said wheel, a source of fluid, a fluid conductor circuit between said source and motor, a pump in said conductor circuit for pumping fluid from said source to said motor, and means operatively connected thereto for adjustably limiting the pressure of fluid in said motor.

3. In combination with a rotary grinding wheel of a grinding machine, a wheel truing mechanism comprising a crushing roll, means supporting said roll on said machine for rotation about an axis substantially parallel to that of said wheel and for motion toward and from said wheel, a fluid pressure motor connected to said roll for moving said roll against said wheel and there holding it under pressure from said fluid, said motor having a continuously open bleeder port for the escape of fluid under pressure therefrom, means connected thereto biasing said roll to a position retracted from said wheel, a source of fluid, a fluid conductor circuit between said source and motor, a pump in said conductor circuit for pumping fluid from said source to said motor, means operatively connected thereto controlling the operation of said pump, and means operatively connected thereto and actuated automatically when said roll has reached a determined feed position to actuate said controlling means to stop said pump.

4. The combination with a grinding wheel and

means supporting said wheel for rotation, a ram mounted for axial motion toward and from said grinding wheel, a wheel crusher roll journaled on said ram for motion by motion of said ram toward and away from the periphery of said wheel, a piston connected to said ram, a stationary hydraulic cylinder within which said piston is slidable, means operatively connected thereto for forcing hydraulic fluid into said cylinder back of said piston to force said crusher roll against said wheel, means operatively connected thereto for controlling said forcing means, said cylinder having a continuously open bleeder port for the escape of fluid from said cylinder, and means operatively connected thereto biasing said ram in a direction to retract said roll from said wheel.

5. The combination with a grinding wheel and means supporting said wheel for rotation, of a ram mounted for axial motion toward and from said grinding wheel, a wheel crusher roll journaled on said ram for motion by motion of said ram toward and away from the periphery of said wheel, a piston connected to said ram, a stationary hydraulic cylinder within which said piston is slidable, means operatively connected thereto for forcing hydraulic fluid into said cylinder back of said piston to force said crusher roll against said wheel, means operatively connected thereto for controlling said forcing means, means operatively connected thereto for adjustably limiting the maximum pressure of fluid in said cylinder, said cylinder having a continuously open bleeder port for the escape of fluid from said cylinder, and means operatively connected thereto biasing said ram in the direction to retract said roll from said wheel.

6. The combination with the grinding wheel of a grinding machine and means including a motor operatively connected thereto for rotating said wheel about its axis, a crushing roll mounted for motion on said machine toward and from said grinding wheel, means operatively connected thereto for moving said roll toward and pressing it against said grinding wheel, a pair of controls for said motor selectively associable therewith, one of said controls when effective causing said motor to rotate at fast grinding speed in grinding direction, and the other of said controls when effective causing said motor to rotate at slow crushing speed in crushing direction, means operatively connected to said controls and operator actuatable to stop said motor and wheel from fast grinding speed, to actuate said roll moving means to press said roll against said grinding wheel while said grinding wheel is stationary and to select said slow wheel rotating means for operative connection to said motor, means operatively connected thereto and operator actuated to activate said slow wheel rotation means to rotate said wheel at slow crushing speed while said crushing roll is pressed against said wheel, means operatively connected to said control means and to said crushing roll reversing said roll moving means to withdraw said crushing roll when said roll has been moved against said wheel to a predetermined extent, to then stop said motor and roll moving means, and to change from said slow rotating to said fast rotating motor control.

7. The combination with the grinding wheel of a grinding machine and means including a motor operatively connected thereto for rotating said wheel about its axis, a crushing roll mounted for motion on said machine toward and from said

grinding wheel, means operatively connected thereto for moving said roll toward and pressing it against said grinding wheel, a pair of controls for said motor selectively associative therewith, one of said controls when effective causing said motor to rotate at fast grinding speed in grinding direction, and the other of said controls when effective causing said motor to rotate at slow crushing speed in the direction reverse to said grinding direction, means operatively connected to said controls and operator actuatable to stop said motor and wheel from fast grinding speed, to actuate said roll moving means to press said roll against said grinding wheel while said grinding wheel is stationary and to select said slow wheel rotating means for operative connection to said motor, means operatively connected thereto and operator actuated to activate said slow wheel rotation means to rotate said wheel at slow crushing speed while said crushing roll is pressed against said wheel, means operatively connected to said control means and to said crushing roll reversing said roll moving means to withdraw said crushing roll when said roll has been moved against said wheel to a predetermined extent, to then stop said motor and roll moving means, and to change from said slow rotating to said fast rotating motor control.

8. In combination with the grinding wheel of a grinding machine, said wheel being mounted for rotation about its axis, a crushing roll mounted on said machine and movable toward and from said grinding wheel, means biasing said roll away from said grinding wheel, means operatively connected thereto for rotating said wheel in grinding direction at fast speed, means operatively connected thereto for rotating said grinding wheel in crushing direction at low speed, means operatively connected thereto for moving said roll against the action of said biasing means into crushing relation to said grinding wheel, operator actuatable means operatively connected thereto for starting said wheel rotating means, means dependent upon both of said rotating means being out of operation and actuatable by the operator and operatively connected thereto to actuate said roll moving means to move said roll against said grinding wheel and to condition said starting means to actuate said slow wheel driving means, and means operatively connected to said roll and automatically actuated after the starting of said slow wheel driving means when said roll reaches a predetermined crushing position to stop said roll moving means and to permit said biasing means to retract said roll from said wheel, and means operatively connected to said roll and rotating means and actuated by such retraction to a predetermined point to stop said slow wheel rotating means and start said fast wheel rotating means.

9. In combination with the grinding wheel of a grinding machine, said wheel being mounted for rotation about its axis, of a crushing roll mounted on said machine and movable toward and from said grinding wheel, means operatively connected thereto biasing said roll away from said grinding wheel, means operatively connected thereto for rotating said wheel in grinding direction at fast speed, means operatively connected thereto for rotating said grinding wheel in crushing direction at low speed, means operatively connected thereto for moving said roll against the action of said biasing means into crushing relation to said grinding wheel, operator actuatable means connected thereto for start-

ing said wheel rotating means, means dependent upon both of said rotating means being out of operation and actuatable by the operator and operatively connected thereto to actuate said roll moving means to move said roll against said grinding wheel and to condition said starting means to actuate said slow wheel driving means, and means operatively connected to said roll and automatically actuated after the starting of said slow wheel driving means when said roll reaches a predetermined crushing position to stop said roll moving means and after a dwell of predetermined time to permit said biasing means to retract said roll from said wheel, and means operatively connected to said roll and slow and fast rotating means and actuated by such retraction to a predetermined point to stop said slow wheel rotating means and start said fast wheel rotating means.

10. In combination with the grinding wheel of a grinding machine, said wheel being mounted for rotation about its axis, of a crushing roll mounted on said machine and movable toward and from said grinding wheel, means operatively connected thereto biasing said crushing roll to retracted position away from said grinding wheel, an electric motor for rotating said wheel, a pair of actuating circuits for said motor, one of said circuits when energized rotating said motor in grinding direction at a fast grinding speed, the other of said circuits when energized rotating said motor in crushing direction at slow speed, a manual switch operatively connected thereto for energizing selectively one or the other of said circuits, a second motor connected thereto and actuatable to move said roll from retracted position toward said wheel, control means for said second motor conditioned by the deenergization of both of said circuits to energize said second motor to move said roll against said wheel, said manual switch then being actuatable to energize the other of said circuits to cause slow rotation of said wheel in crushing direction, means operatively connected to said roll and second motor and actuatable by the motion of said roll to a predetermined point to deenergize said second motor and allow said biasing means to retract said roll, and means operatively connected to said roll and circuits and actuated by the retraction of said roll to a predetermined point to deenergize said other circuit and to energize said one circuit to thereby cause said grinding wheel to rotate at high speed in grinding direction.

11. In combination with the grinding wheel of a grinding machine, said wheel being mounted for rotation about its axis, of a crushing roll mounted on said machine and movable toward and from said grinding wheel, means biasing said crushing roll to retracted position away from said grinding wheel, an electric motor connected thereto for rotating said wheel, a pair of actuating circuits for said motor, one of said circuits when energized rotating said motor in grinding direction at a fast grinding speed, the other of said circuits when energized rotating said motor in crushing direction at slow speed, a manual switch operatively related to said circuits for energizing one or the other of said circuits, a second motor connected to said roll and actuatable to move said roll from retracted position toward said wheel, control means for said second motor conditioned by the deenergization of both of said circuits to energize said second motor to move said roll against said wheel, said manual switch then being actuatable to energize the other of said

13

circuits to cause slow rotation of said wheel in crushing direction, means operatively connected thereto and actuatable by the motion of said roll to a predetermined point to stop the motion of said crushing roll and after a predetermined time interval to deenergize said second motor and allow said biasing means to retract said roll, and means operatively connected to said roll and circuits and actuated by the retraction of said roll to a predetermined point to deenergize said other circuit and to energize said one circuit to thereby cause said grinding wheel to rotate at high speed in grinding direction.
